MULTIPLE FILAMENT LAMP SWITCH

Fletcher A. Wilkins, Indianapolis, Ind.

Application July 22, 1938, Serial No. 220,611

5 Claims. (Cl. 176—27)

This invention relates to controlling means for a multiple filament lamp and has for a primary object the incorporation of the switching means within the standard size lamp base so that the

5 lamp may be operated in any standard socket.

A further primary object of the invention is to provide a switching mechanism in the position above indicated which may be operated by a flexible cord or chain so as to permit the lamp to be

10 mounted in any position within shades and the like so that the flexible member may be extended from the fixture for remote control if desired without interfering in any way with surrounding members such as the shade.

15 These and other objects and advantages of the invention, including the unique assembly of the various elements in the association as set forth by the appended claims, will become apparent to those versed in the art in the following description of one particular form of the invention as now best known to me. Referring to the accompanying drawings which illustrate the invention,

Fig. 1 is a side elevation of a lamp embodying the invention with parts in section;

20 Fig. 2, a detail in enlarged elevation and partial section;

Fig. 3, a base end plan view;

Fig. 4, a transverse section on the line 4—4 in Fig. 2;

25 Fig. 5, a wiring diagram;

Fig. 6, a detail in transverse section on the line 6—6 in Fig. 4;

Fig. 7, a detail in transverse section on the line 7—7 in Fig. 4;

30 Fig. 8 a detail on an enlarged scale on the line 8—8 in Fig. 3;

Fig. 9, a section on the line 9—9 in Fig. 2; and

Fig. 10, a section on the line 10—10 in Fig. 2.

Like characters of reference indicate like parts

40 throughout the several views in the drawings.

In the form of the invention herein shown, the lamp 15 is provided with a plurality of filaments,

herein shown as two in number. As an example only and not as a limitation of the range of fila-

45 ment capacities, the lamp may have a filament

16 of a 100 watt capacity and the other filament

17 of 50 watt capacity, whereby the lamp may be

operated to have the 50 watt filament energized

50 alone; the 100 watt filament alone; or both fila-

ments simultaneously to give a 150 watts. In

other words, three degrees of illumination may

be secured from the two filaments.

These filaments 16 and 17 are supported in the usual and customary manner by a positioning

55 post 18 and leads 19 and 20 run from the filament

16 together with a third lead 21 from the filament 17 through the sealing tube 22 and out through the base end of the lamp. In this particular form, the lead 19 is also interconnected with one terminal of the filament 17, the lead 21 being carried from the other filament terminal. The lamp 15 is evacuated or gas filled in accordance with standard practice.

Secured to the base end of the lamp 15 in any suitable manner, such as by a cement or plastic 10 23, is an insulating base 24 which is counter-bored at its lamp end to receive the lamp base therewithin. This base 24 is provided with an external cylindrical surface on which screw- 15 threads are formed to receive a ferrule 25 screw-threadedly therearound. This ferrule 25 is provided with external threads standardized to fit the threads of the standard lamp receptacle. Likewise the length of the base 24 and the ferrule 25 therethrough is made to be such as to be prac- 20 tically fully received within the standard lamp receptacle as is the usual practice.

The base 24 is provided with a chamber 26 within which all of the switching mechanism is mounted. The chamber 26 is preferably rectangular in shape and opens at its base end. A cover 27, made out of any suitable insulating material, is generally circular in shape and has a central boss 28 extending rearwardly to protrude through a circular opening formed centrally within the 30 base end of the ferrule 25, the ferrule being flanged over on its base end so as to draw the cover 27 compressively against the end of the base 24 when the ferrule 25 is screwed snugly into position on the base 24. The cover 27 is prefer- 35 ably pinned into position so as to prevent rotation. Dowel pins 29 and 30 extend from the rear end of the base 24 and fit into holes preferably spaced in the cover 27. A rivet or screw 31, as herein shown, extends centrally through the boss 28 of 40 the cover 27 to engage a conductor bar 32 on the inside of the cover 27. This bar 32 is drawn compressively against the cover 27 and is held against rotation by means of a pin 33 extending from the cover 27 and entering a hole in the bar. This bar 45 32 further carries a pair of spaced apart contact fingers 34 and 35 curving around from the bar and inwardly within the chamber 26.

An axle 36 extends centrally, transversely across the chamber 26 to carry a drum 37 thereon. This drum 37 is provided with two annular tracks therearound having a central dividing rib or flange 38 with like end flanges 39 and 40. The drum 37 is preferably made out of some suitable insulating material to have the major portion of 55

the track of an insulating character. On each track is provided a pair of spaced contact members. Referring to the wiring diagram, Fig. 5, these tracks are shown in developed relation where the left hand track carries the contact members 41 and 42. The right hand track carries the contact members 43 and 44. The contact members 42 and 44 are mounted adjacent each other in the two tracks to have the same annular location about the drum. Further, these contact members 42 and 44 are of equal length. The other contact members 41 and 43 are of equal length, the member 41 being spaced around the track from the member 42 and the member 43 being spaced in its track an annular distance away from the member 44 less than the distance of the member 41 from the member 42.

On the inner end or floor of the chamber 26 are mounted a pair of contact fingers 45 and 46. These fingers 45 and 46 are fixed in position by respective ends contacting the floor of the chamber 26 and have free ends elastically bearing against the drum 37, one finger against each track so as to have the respective contact members 41, 42 and 43, 44 come into wiping contact with these fingers 45 and 46 as the drum is turned. The upper fingers 34 and 35 which are carried by the bar 32 likewise elastically bear against the respective drum tracks to be also subject to wiping contact with these respective contact members. The two sides of the contact fingers, however, have their ends spaced apart so that circuits may be only opened and closed by means of the contact members passing between the fingers to close the circuit and then passing on to open it.

The filament 16 has its lead 19 carried up through the base 24 and brought out from a side thereof, Fig. 2, to come into electrical contact with the ferrule 25. The lead 20 is brought up through the floor of the base 24 to connect with the finger 46. The lead 21 of the filament 17 is brought up through the floor of the chamber 26 and is connected to the finger 45.

A spring latch finger 47 is secured to the floor of the chamber 26 by one end and has a free end compressively bearing against the center drum rib 38. This rib 38 is provided with a series of spaced notches 48 into which the end of the latch 47 will drop as the drum 37 is rotated. It is to be noted that these notches are so formed that the drum 37 may be rotated in a clockwise direction, Fig. 10, but held against rotation in the reversed direction by reason of the end of the latch 47 abutting a shoulder of the notch in each instance.

A flexible member, such as a cord or a chain 49 shown in the present form, enters through a side of the base 24 ahead of the ferrule 25 and is carried freely through a passageway into the chamber 26 to have its end secured to a rocker 50 which is essentially a U-shaped member in the nature of a yoke. This yoke 50 has its two legs turned to have the axle 36 pass therethrough in a manner which will permit the yoke 50 to rock freely around the drum 37, the cross-bar between the legs of the yoke being spaced from the drum and normally positioned adjacent the cover 27. The yoke 50 is normally biased to have its upper end rocked toward the fingers 34 and 35 by means of a torsional spring 51 which has one or more turns about the axle 36, one end bearing against a wall of the chamber 26 and the other end against a pin 52 protruding from the yoke. The chamber 26 is provided with a recess within which

the spring 51 is positioned and against a shoulder of which recess the pin 52 will strike to limit the movement of the yoke under the influence of the spring 51 so that the cross-bar of the yoke is normally spaced away from the fingers 34 and 35. 5

On the outer end of the drum 37 adjacent the spring 51 are a series of teeth 53 formed outside of the flange 40 and circumferentially around the drum. The yoke 50 carries a pawl 54 which is normally spring pressed by its free end into the path of these teeth 53. The pawl 54 extends in an annular position in the direction of the pull of the chain 49 on the yoke 50 so that when the chain 49 is pulled, the pawl 54 will engage against one of the teeth 53 and thereby pull the drum 37 around a distance equal to the permissible travel of the yoke 50, the yoke 50 in this case being stopped by coming into contact with the side wall of the chamber 26 as indicated by the dash line position in Fig. 8. When the yoke 50 is pulled to this extreme position, the latch 47 will drop into a notch 48 and retain the drum against reverse rotation when the chain 49 is released to allow the spring 51 to return the yoke 50 to its normal initial position. 10 15 20

In operation, it will be assumed that the drum 37 is in an initial position wherein neither filament 16 nor 17 is energized, that is, the circuits of both filaments are open. Then the chain 49 may be pulled and released. This action will rotate the drum 37 to a position wherein, Figs. 2, 5, 9 and 10, the segment 41 is between both fingers 34 and 45. The latch 47 retains the drum in this position upon the release of the chain 49 while the pawl 54 drags back over the teeth 53 as the yoke 50 returns to its normal position under the influence of the spring 51. In this position of the drum, as will be noted in Fig. 5, a circuit is completed between the head of the screw 31, the finger 34, the contact member 41, the lower finger 45, the filament lead 21, the filament 17, the lead 19, and the ferrule 25. This completes the circuit through the smaller or 50 watt filament alone. In this position of the drum, there is no contact member bridging the fingers 35 and 46 so that the filament 16 remains in an open circuit. 30 35 40 45

The next pull on the chain 49 will rotate the drum 37 to the next notch 48 whereby the drum is then held in a position where there are no contact members bridging either pair of contact fingers. Consequently both filaments 16 and 17 are then in open circuits and not energized. Another pull on the chain 49 will rotate the drum 37 one more step to bring the contact member 43 into position to bridge the fingers 35 and 46. This position of the drum then closes a circuit to include the filament 16 only to leave the filament 17 in an open circuit. 50 55

A subsequent pull on the chain 49 will rotate the drum 37 again to the next notch 48 engagement with the latch 45 to carry the contact member 43 on around and leave an open circuit between both sets of fingers again so as to provide another "off" position for both filaments 16 and 17. 60 65

Again pulling the chain 49 will rotate the drum 37 to bring both contact members 42 and 44 to bridge the respective fingers 34, 45 and 35, 46. In this position of the drum, circuits are closed through both filaments 16 and 17 to give the full 150 watt illumination. The next pull on the chain 49 will rotate the drum 37 to remove all contact members from between both sets of fingers so as to leave both filaments again in open 70 75

circuits. Subsequent pulls on the chain 49 will repeat the above indicated actions.

It is to be noted that arcing is reduced to a minimum by notching out the periphery of the drum in the tracks wherein the various fingers ride so as to have the fingers snap off of the ends of the contact members on the drum to give a quick, wiping break.

While I have herein shown and described my invention in the one particular form, it is obvious that structural details may be changed without departing from the spirit of the invention, and I, therefore, do not desire to be limited to that precise form beyond the limitations as may be imposed by the following claims.

I claim:

1. In a multiple filament lamp having a base of insulation with a cavity therein, an insulating cover closing said cavity, an axial terminal extending through the cover, a metallic sleeve ferrule for socket attachment fitting over and secured to said base around that portion thereof including said cavity, a drum rotatably positioned within said cavity on a transverse shaft, a plurality of electrical contacts spaced one from the other on said drum, upper contact fingers carried by said cover and each connected with said terminal to extend yieldingly against said drum in the paths of said contacts, lower contact fingers fixed in said cavity to be pressed yieldingly against said drum, whereby said drum contacts selectively bridge said upper and lower fingers electrically with said terminal upon suitable rotation of said drum, a ratchet mechanism for rotating the drum, a ratchet operating member extending from said base below said ferrule, a separate filament being provided in said lamp for and in electrical connection with each of said lower fingers, and all of said filaments being electrically connected with said ferrule, said ratchet operating member consisting of a member within said cavity and rockable on said drum shaft, spring means normally holding the member in an initial position, a plurality of teeth spaced circumferentially apart around a part of said drum, and a pawl carried by the rockable member in the path of said teeth and spring pressed thereagainst, and said ratchet operating member consisting of a flexible pull line fixed to said rockable member and guided through the base toward the lamp and then carried outwardly externally of the base.

2. A multiple filament lamp as defined by claim 1, said rockable member being U-shaped to straddle said drum and engage the drum shaft on each end of the drum, said pawl being mounted between one leg of the rockable member and the drum.

3. A multiple filament lamp as defined by claim 1, said drum being provided with a plurality of laterally spaced tracks in which said electrical contacts are placed, ribs projecting from the drum defining annular walk along the tracks, a plurality of notches in one of said ribs corresponding in number to the total number of "on" and "off" positions of the drum, and a latch member mounted in the cavity yieldingly bearing against said rib to engage in said notches and retain the drum in a rotated position while said rockable member returns to its said initial position.

4. A multiple filament lamp as defined by claim 1, said drum being provided with a plurality of laterally spaced tracks in which said electrical contacts are placed, ribs projecting from the drum defining annular walk along the tracks, a plurality of notches in one of said ribs corresponding in number to the total number of "on" and "off" positions of the drum, and a latch member mounted in the cavity yieldingly bearing against said rib to engage in said notches and retain the drum in a rotated position while said rockable member returns to its said initial position, and a stop in said cavity limiting rocking of said member when rocked by said line.

5. A multiple filament lamp as defined by claim 1, said drum being provided with a plurality of laterally spaced tracks in which said electrical contacts are placed, ribs projecting from the drum defining annular walk along the tracks, a plurality of notches in one of said ribs corresponding in number to the total number of "on" and "off" positions of the drum, and a latch member mounted in the cavity yieldingly bearing against said rib to engage in said notches and retain the drum in a rotated position while said rockable member returns to its said initial position, and a stop in said cavity limiting rocking of said member when rocked by said line, said contacts being insulated one from the other and positioned around said tracks to provide open circuits between upper and lower pairs of fingers following each closed circuit position.

FLETCHER A. WILKINS.
